UNITED STATES PATENT OFFICE.

CHARLES FRANKLIN ECKART, OF HONOLULU, TERRITORY OF HAWAII, ASSIGNEE OF
ONE-HALF TO WILLIAM GARVIE HALL, OF HONOLULU, TERRITORY OF HAWAII.

EVAPORATOR.

1,053,017.

Specification of Letters Patent. Patented Feb. 11, 1913.

Application filed December 19, 1911. Serial No. 666,651.

To all whom it may concern:

Be it known that I, CHARLES FRANKLIN ECKART, a citizen of the United States, residing at Honolulu, in the county of Honolulu and Territory of Hawaii, have invented 5 certain new and useful Improvements in Evaporators; and I do hereby declare the following to be a full, clear, and exact description of the invention, such as will enable others skilled in the art to which it appertains to make and use the same.

This invention relates to evaporators, particularly to the standard or submerged tube type of evaporator.

15 The object of the invention is to increase the efficiency of the evaporator by reducing the vapor tension on the surface of the liquor, increasing the upward flow of vapor, and by decreasing the restraining effect 20 (upon evaporation) of the supernatant air, vapor or other gases on the surface of the liquor.

The invention contemplates a fan or the like adapted to revolve in a horizontal plane 25 immediately above the surface of the liquor to be evaporated above the top of the calandria, and means for revolving said fan or the like in any suitable manner. In evaporators of the type mentioned, the liquor 30 under treatment rises within the tubes of the calandria and flows rapidly downward through the larger tube or pipe at the center of the calandria, this circulation of the liquor being effected by the introduction of 35 steam or vapor in the calandria and thereby imparting heat to the liquor.

The invention further contemplates the utilization of this downward flow of the liquor through the center pipe of the calandria to propel the above mentioned fan or the like, as will hereinafter more fully appear.

The following is a specific description of one form of the invention, while the actual 45 scope thereof is defined in the appended claims.

The accompanying drawing, forming a part of this specification, is a sectional elevation through the center of the lower portion 50 of an evaporator cell, illustrating my invention.

Referring to the drawing, the usual calandria in the standard type of evaporator consists of a vapor or steam belt 1, supported 55 by beams 2, the upper tube plate 3, the

lower tube plate 4, the tubes 5, and the center pipe 6. The belt 7 is bolted above the upper tube plate 3, and the bottom 8 which is provided at its center with the outlet 9 is bolted below the lower tube plate 4 in the usual manner, as shown. A deflecting cone 10, supported by feet 11 above the outlet 9, is provided as shown, its function being to divert the flow of liquor from the center pipe 6 and cause same to flow 65 outwardly and under the lower tube sheet 4 and thereby prevent same from passing directly downward and out through the outlet 9.

The vertical shaft 12, with its lower end 70 in a suitable step box 13 supported at the apex of the cone 10, and journaled in a suitable anti-friction bearing 14 supported by a brace 15 to the upper tube sheet 3, is adapted to be revolved. If desired, the 75 lower end of the shaft 12 may have a hardened point and the step box 13 may have a suitable jeweled bearing in which said point may turn. The shaft 12 is provided with a screw 16 or the like between the step box 13 and the bearing 14. A fan 17 or the like is secured to the shaft 12 with its arms extending outward horizontally and immediately above the level of the liquor 80 above the upper tube plate 3.

It will now be noted, that when the liquor rushes down the center pipe 6 it will engage the screw 16 and cause same to revolve the shaft 12 to which the fan 17 is attached. The fan 17 in revolving reduces the vapor 90 tension on the surface of the liquor, increases the upward flow of the vapor in the belt 7, and decreases the restraining effect of the supernatant air, vapor or other gases upon the liquor flowing over the upper tube 95 plate 3, and that consequently the efficiency of the evaporator is increased.

In carrying out the invention, in order that same may be operative, the size and pitch of the screw 16 and of the fan 17 100 must be so proportioned, to suit the conditions in each case, that the action of the downward flow of the liquor upon the screw 16 shall in each case exceed the resistance offered to the fan 17 by the vapors it 105 encounters when revolving as well as overcome the friction of the shaft 12.

I claim:

1. In an evaporator, a fan or the like immediately above the surface of the liquor, 110

and means for revolving said fan or the like, for the purpose as specified.

2. In an evaporator, a fan or the like propelled by the circulating liquor, substantially as and for the purpose as specified.

3. In an evaporator, a vertical shaft adapted to revolve in the center of the evaporator, a screw or the like secured to said shaft and adapted to be revolved by the circulating liquor, and a fan or the like attached to said shaft above said screw, substantially as and for the purpose described.

4. In an evaporator, a vertical shaft adapted to revolve in the center of the evaporator, a fan attached to said shaft and means associated with said shaft adapted to

be actuated by the circulating liquor to revolve said fan.

5. In an evaporator, the combination with the calandria tubes of a center tube, a shaft 20 mounted for rotation in said center tube, a fan attached to said shaft above the calandria tubes and means associated with said shaft adapted to be actuated by the liquor flowing through said center tube to revolve 25 said fan.

In testimony whereof I affix my signature, in presence of two witnesses.

CHARLES FRANKLIN ECKART.
